UNITED STATES PATENT OFFICE.

JOSEPH A. BUNNELL, OF NEW YORK, N. Y., ASSIGNOR OF ONE-HALF TO
JAMES THOMPSON ROBB, OF SAME PLACE.

INSULATED BALL-JOINT.

SPECIFICATION forming part of Letters Patent No. 356,614, dated January 25, 1887.

Application filed September 9, 1886. Serial No. 213,183. (No model.)

To all whom it may concern:

Be it known that I, JOSEPH A. BUNNELL, a citizen of the United States, residing at New York, in the county and State of New York, 5 have invented new and useful Improvements in Insulated Ball-Joints, of which the following is a specification.

The object of this invention is to provide an insulated ball-joint. The manner of constructing said ball-joint is set forth in the following specification and claims, reference being made to the accompanying drawings, in which—

Figure 1 is a longitudinal central section of a ball-joint. Fig. 2 is a section in the plane α α , Fig. 1. Fig. 3 is a side elevation of an insulator. Fig. 4 is an elevation of one ball-section. Fig. 5 is a longitudinal central section of another ball-section. Fig. 6 is a longitudinal central section of a modification.

Similar letters indicate corresponding parts. The letter B indicates the socket within which rests the ball. The ball is made of two tubular or hollow sections, A X. The sections A X are detachably engaged the one 25 with the other by screw-threads. A washer, F, enables the joint between the sections A X to be firmly closed, so as to prevent leakage between said sections. To insulate said joint, an insulator, I, of hard rubber or other 30 fit material, is suitably applied to the joint. In the example shown in the drawings the insulator I lines or partly lines the section X. The insulator I is provided with means—such, for example, as a screw-thread—for attaching 35 a stem or a pipe-section, C. The screw-thread can be formed directly in the insulator I; but as such insulator may consist in some instances of material which is not strong enough to stand a severe strain, it is well in such cases 40 to form said screw-thread in a bushing or thimble, H, of metal or other suitable and strong material. The thimble or bushing H, with its screw-thread, is inserted into the insulator I, so that said insulator surrounds and insulates the thimble H.

The ball-section X, the insulator I, and the bushing H, with the screw-thread, can be firmly joined together by properly shaping or tapering said parts and by providing said 50 several parts with screw-threads, as seen in Fig. 1, so that said parts will screw into one

another, and after said parts are properly joined the ball-section A is screwed into place on the ball-section X, thus preventing said insulator and bushing from coming out of their 55 places.

In case the stem or pipe section C passes some distance into or through the ball-section X, said stem C may come into contact with the ball-section A. By providing the ball-section A with an insulator, G, said stem C will remain insulated, even if said stem C passes through the section X. The insulator G can be formed of a ring or disk of hard 65 rubber or other fit material, and soldered or otherwise fastened in a seat or recess in the ball-section A. By making the washer F also of insulating material, danger of improper connection by means of the washer F is avoided.

The socket B is provided with a screw-thread for the attachment of a stem or pipe section, E. This screw-thread may be formed on a thimble or bushing, D, as seen in Fig. 1, which thimble is soldered or suitably fastened in the socket B; or said screw-thread may be 75 formed directly on the socket B, as seen in Fig. 6, where the stem E is screwed directly onto the socket B.

The socket B can be formed of one piece of material, as seen in Fig. 1, and drawn or spun 80 about the ball A X; or, as seen in Fig. 6, the socket B can be formed of two sections suitably joined—as, for example, by screw-threads.

In some cases—as, for example, where the ball-joint is used to suspend electric illuminating apparatus—it is advisable to limit the motion of the joint, as otherwise by continued turning of the joint the wires or conductors of electricity might be twisted, torn, or broken. To limit such motion of the joint, a stop or 85 detent, K, is applied. This detent can be formed of a pin or projection on the socket B entering a slot in the ball A X, as seen in Fig. 1, or the pin or projection can be formed on the ball and made to enter a suitable slot in the socket, as 90 seen in Fig. 6.

In those cases where the ball-joint is used to support gas-burners or gas-chandeliers the insulators should be formed of such non-conducting material as is not affected by gas—such, for 100 example, as the material known to the trade as “fiber.” To insure a close sitting of the ball

in its socket, a spring, L, Fig. 6, may in some cases be employed to hold the ball in its seat. The material known as "fiber" is a poor conductor of electricity, and in case fiber is employed to insulate the ball-joint said joint can be used to support a gas-burner or gas-chandelier, and also one or more electric lights, the insulated ball-joint preventing improper circuits of the electric current.

10. What I claim as new, and desire to secure by Letters Patent, is—

1. An insulated ball-and-socket joint consisting of the two tubular ball-sections A X, detachably connected together, an insulator, I, lining the section X, and the socket B, inclosing the said two sections, substantially as described.

2. An insulated ball-and-socket joint consisting of the two tubular ball-sections A X, detachably connected by screw-threads on one en-

20 gaging screw-threads in the other, an insulator, I, lining the ball-section X, and the socket B, inclosing the said ball-sections, substantially as described.

25 3. An insulated ball-and-socket joint consisting of the tubular ball-sections A X, detachably united by a screw-threaded connection, the insulator I, lining the ball-section X, the washer F between the ball-sections, the insulator-ring G, seated in a recess in the ball-section A, and the socket B, inclosing the ball-sections, substan-

30 tially as described.

4. An insulated ball-and-socket joint consisting of the two tubular ball-sections A X, detachably connected together, the insulator I, lining the ball-section X, the socket B, having screw-threads for the attachment of a pipe, E, and a detent or stop, K, composed of a pin extending inwardly from the socket B and engaging a slot in the ball-section A, substan-

40 tially as described.

5. An insulated ball-and-socket joint consist-

ing of the two tubular ball-sections A X, detachably united by screw-threads on one engaging screw-threads in the other, an insulator, I, lining the ball-section X, the socket B, inclosing the ball-sections, and the detent or stop K, composed of a pin extending inwardly from the socket and engaging a slot in the ball-section A, substantially as described. 45

6. An insulated ball-and-socket joint consisting of the tubular ball-sections A X, united by screw-threads, the insulator I, lining the ball-section X, the washer F between the ball-sections, the insulator-ring G, seated in a recess in the ball-section A, the socket B, inclosing the 55 ball-sections, and the detent or stop K, composed of a pin extending inwardly from the socket and engaging a slot in the ball-section A, substantially as described.

7. An insulated ball-and-socket joint consisting of the two ball-sections A X, detachably screw-threaded together, the insulator I, lining the ball-section X, the internally-threaded thimble H, seated in the inner end of the insulator-lining, and the socket B, inclosing the 65 ball-sections, substantially as described.

8. An insulated ball-and-socket joint consisting of the two tubular ball-sections A X, one screwed into the other, the insulator I, lining the ball-section X, the internally-threaded 70 thimble H, seated in the inner end of the insulator-lining, the insulator-ring G, arranged in a recess in the ball-section A, and the socket B, inclosing the ball-sections, substantially as described.

In testimony whereof I have hereunto set my hand and seal in the presence of two subscribing witnesses.

JOSEPH A. BUNNELL. [L. S.]
